UNITED STATES PATENT OFFICE

128,489

DESIGN FOR A SET OF GAME PIECES

Roger K. Harlan, Dallas, Tex.

Application December 11, 1940, Serial No. 97,261

Term of patent 7 years

To all whom it may concern:

Be it known that I, Roger K. Harlan, a citizen of the United States, residing at Dallas, in the county of Dallas and State of Texas, have invented a new, original, and ornamental Design for a Set of Game Pieces, of which the following is a specification, reference being had to the accompanying drawing, forming part thereof, in which:

Figs. 1 and 1a are, respectively, an elevation and a plan view of a game piece representing a capitol;

Figs. 2 and 2a are, respectively, an elevation and a plan view of a game piece representing a ship;

Figs. 3 and 3a are, respectively, a front view

and a side elevation of a game piece representing a tank;

Figs. 4 and 4a are, respectively, a front view and a side elevation of a game piece representing a general;

Figs. 5 and 5a are, respectively, an elevation and a plan view of a game piece representing a bomb; and

Figs. 6 and 6a are, respectively, an elevation and a plan view of a game piece representing a fighter or private.

I claim:

The ornamental design for a set of game pieces, as shown.

ROGER K. HARLAN.
